UNITED STATES PATENT OFFICE.

GEORGE G. CAMPANA, OF NEW YORK, N. Y., ASSIGNOR, BY MESNE ASSIGNMENTS, OF ONE-HALF TO THE THOMAS LASTING WAVE CO., OF NEW YORK, N. Y., A CORPORATION OF NEW YORK.

HAIR-CURLER.

1,269,158.

Specification of Letters Patent. Patented June 11, 1918.

Application filed June 9, 1916. Serial No. 102,616.

To all whom it may concern:

Be it known that I, GEORGE G. CAMPANA, a subject of the King of Italy, and a resident of the city, county, and State of New York, have invented certain new and useful Improvements in Hair-Curlers, of which the following is a specification.

My invention relates to a waver used in forming permanent waves or undulations to 10 the hair on a person's head.

In the present method of forming permanent hair waving it is necessary to separate the hair into strands and wrap these strands in a tight coil on some form of curler 15 usually a straight rod or a rod such as is shown in the patent to Grosert, No. 1085083, Jan. 20, 1914. Prior to the wrapping step it is usual to gather the strand of hair and turn it into a twist and while holding the 20 hair in its twisted position, to tie the end of the strand adjacent the head with a small length of string. The loose portions of the string are then tied about the curler with the head of the curler as close as possible 25 to the end of the twisted strand adjacent the person's head. The loose ends of the string must then be cut short so as not to interfere with the succeeding wrapping operation. This dual operation requires the 30 presence of two operators and it is exceedingly difficult to properly position the curler so as to take the loop formed in the string after it has been passed about the strand of hair. Accordingly one of the objects of my 35 invention is to provide a device of the above indicated character designed so that the twisted strand of hair may be fixed to the curler without the necessity of any tying operation or the use of fastening means, 40 such as strings.

It is among the other objects of the invention to provide a device of the above indicated character upon which the hair may be wound with a regular spacing of the 45 coils of hair and which may be readily separated from the caked cementitious composition usually present at the termination of the heat treatment forming part of the permanent hair waving operation.

I attain these objects broadly by providing a waver having the tapered design so necessary to the perfect formation of the waved hair and somewhat in the nature of

a pair of forceps provided with peculiarly shaped tong ends designed to grasp the 55 twisted hair adjacent the person's head.

Various other objects and advantages of the invention will be in part obvious from an inspection of the accompanying drawings and in part will be more fully set forth 60 in the following particular description of one form of mechanism embodying my invention, and the invention also consists in certain new and novel features of construction and combination of parts hereinafter 65 set forth and claimed.

Figure 1 is a perspective view of a head of hair showing a twisted strand coiled about my improved waver;

Fig. 2 is a side view of a preferred form 70 of my invention with parts broken away to show the spring; and

Fig. 3 is an edge view of the device shown in Fig. 2 looking at the same from the left hand side.

The curler includes a channel shaped thin sheet metal member 4 of greatest depth adjacent its middle portion, and with the flanges tapering in depth toward opposite ends. The back or crotch portion of the 80 channel is rounded into the flanges and is provided at one end with a flat extension. The extension is substantially elliptical in form and provided with a notch 6 at its outer edge. The channel portion is cut away 85 at the end opposite the extension to provide a recess to accommodate the lateral extension from a coacting member hereinafter described and to guide the coacting member. The coacting member is in the form of a 90 substantially round bar 7 pivotally supported on a pin 8 passed therethrough intermediate its length and fastened in opposite flanges of the channel member 4. One end of the bar is provided with a lateral extension 95 95 designed to pass through the recess in the adjacent end of the channel member to prevent distorting strains on the pivot pin when the device is in use. The end of the bar opposite the end provided with the 100 extension is reduced as shown in Fig. 3 and the reduced portion bent back upon itself and then curved forward to form a hook 10 designed to fit within the notch 6 when the members are in closed position. 105 A spring 11 is positioned within the channel

member 4 and bears on this member and on the rod 7 to maintain the extension 5 and the hook 10 in inter-engaging position.

The peculiar hook construction, shown at 5 10, permits the hair to be wound about the curler in either direction.

As all string fasteners are eliminated from the process when this form of curler is used, the danger of cutting the hair which was 10 very apt to occur under the old process when the string was clipped at the end of the heating treatment, is entirely avoided.

In operation, it is understood that the hair is combed out straight and separated 15 into strands. One of the strands is then taken and twisted about its own length and while holding the twisted strand in one hand the operator takes the waver in his other hand, bears on the handle end to open the 20 clamping jaws formed by the extension 6 and hook 10 and inserts the same about the base of the hair with the waver extending substantially at right angles to the length of the twisted strand of hair. Releasing 25 pressure on the handle end of the device will permit the spring 11 to close the jaws into position grasping the hair. Holding the device adjacent its free end the operator can conveniently wrap the hair in a coil 30 about the waver as is practised at present but without the necessity of requiring the presence of two operators.

It will be noted that when in position on the hair the device increases in cross-section 35 from the end adjacent the head outward, thus permitting the wrapping of the thick portion of the strand on the small end of the waver and as the thickness of the strand becomes reduced toward its free end 40 the waver correspondingly increases in circumference so that when the process is completed the waves are uniformly spaced as shown in the right hand side of Fig. 1.

While I have shown and described, and 45 have pointed out in the annexed claims, certain novel features of my invention, it will be understood that various omissions, substitutions and changes in the form and details of the device illustrated and in its 50 operation may be made by those skilled in the art without departing from the spirit of the invention.

Having thus described my invention, I 55 claim:

1. A device of the class described including a pair of straight members relatively small in cross-section pivoted intermediate their ends and coacting to provide exterior hair receiving surfaces, the adjacent ends of the 60 members at one end of the device provided with means coacting to fasten a strand of hair to the device, a spring acting on said members to move said hair fastening means into closed position, said members coacting 65 to provide a curler substantially circular in

cross-section upon which the fastened strand of hair may be wrapped in a coil.

2. A hair waver for use in forming the hair on a person's head into waves, said waver constituting a forceps provided with 70 clasp means designed to engage the strand of hair adjacent the person's head and thus secure the waver in position, said waver increasing in circumference progressively from said clamping means toward the 75 opposite end whereby the progressively thinner coils of the hair may be arranged in succession on progressively larger portions of the waver.

3. A hair waver for use in forming the 80 hair, on a person's head into waves, comprising a pair of substantially straight members pivoted together approximately at their centers, providing a curved surface for receiving the coil of hair wound thereon, 85 adjacent ends of said members being provided with means coacting to clasp a strand of hair therebetween, the portion of the waver in rear of said hair clasp means constituting, in effect, a rod upon which the 90 hair may be wrapped in a circular coil, and resilient means for moving said members in their hair grasping position.

4. A hair waver for use in forming the 95 hair on a person's head in waves, comprising a pair of members, means pivotally connecting said members, adjacent ends of said members being provided with means coacting to 100 clasp a strand of hair therebetween, and to hold the same against slippage, the portion of the members between the pivoting means and said clasp means coacting to form a curling rod, resilient means for maintaining said members in their hair 105 grasping position and means at the handle end of the members for guiding said members in their relative movement.

5. A hair waver for use in waving the hair on a person's head, comprising a single channel member having a hair engaging extension at one end and provided with a 110 surface for receiving the coil of hair, a bar pivoted between the flanges of said channel member, one end of said bar being provided with a hook designed to coact with said extension to clasp the hair therebetween, the portion of the channel member and bar between the pivotal point and said hook and extension coacting to 115 form a curling rod, and a spring carried by the channel member and bearing on the bar to maintain the hook and extension in clasp- 120 ing position.

6. A hair waver for use in waving the hair 125 on a person's head, comprising a channel member having a hair engaging extension at one end, a bar pivoted between the flanges of said channel member, one end of said bar being provided with a hook designed to coact with said extension to clasp the hair 130

therebetween, a spring carried by the channel member and bearing on the bar to maintain the hook and extension in clasp⁵ position and means at the end of the bar opposite the hook end designed to coact with the channel member to guide said bar and member in their relative movement and to relieve strain on the pivotal connection.

7. In a device of the class described, a hair clasp¹⁰ device including a curved hair coil forming member provided with a flat extension adapted to have a strand of hair laid across the same and provided with a notch and a coacting hook member designed to lap the strand of hair and to engage in said notch to hold the hair.

8. In a device of the class described, a hair clasp¹⁵ device including a curved hair coil forming member provided with an extension which is provided with a notch, a coacting hook member designed to engage in said notch to hold the hair and means for guiding the hook into the notch.

9. In a device of the class described, a hair clasp²⁰ device including, a curved hair coil forming member provided with an extension which is provided with a notch, a coacting hook member designed to engage in said notch to hold the hair, means for guiding the hook into the notch and resilient means for moving the hook and notched extension into hair clasp²⁵ position.

10. A hair curler comprising a pair of members pivoted together, one of said members including an extension provided with a notch, the other member provided with a hook designed to engage in said notch to hold the hair.

Signed at New York city in the county of New York and State of New York this eleventh day of May, A. D. 1916.

GEORGE G. CAMPANA.
